Application January 21, 1937, Serial No. 121,502
In Norway January 17, 1936

8 Claims.

(Cl. 92—44)

In paper-machines which run at high speeds difficulties are caused by air bubbles or foam on the wire-cloth which form thin and transparent spots in the paper. For destroying such air bubbles it is usual to blow hot air or steam against the paper web on the wire-cloth, or water jets may be employed.

Such air bubbles are formed by the wire-cloth, which moves at a high rate of speed over the breast-roller and past the mouth of the pulp outlet through which the pulp is supplied to the upper side of the wire-cloth, carrying along air through the narrow space between the breast-roller and the pulp outlet and past the mouth of the latter to the lower side of the web of pulp delivered to the wire-cloth. It is the object of the present invention to prevent air bubbles from being formed in this manner. This object is attained by submitting the space immediately in front of the pulp outlet to a reduced air pressure. For this purpose there is provided below the outlet and in front of the upward moving portion of the breast-roller covered by the wire-cloth, a closed chamber or box in which a reduced air pressure can be maintained, and one wall of which is formed by the surface of said breast-roller, said chamber or box extending to the space between the pulp outlet and the wire-cloth, so that the wire-cloth runs through the said chamber just before it moves in below the said outlet. By maintaining a sufficiently reduced air pressure in said chamber or box there will be no flow of air in the direction of movement of the wire-cloth, and no air will be carried along by the wire-cloth passing through the chamber or box to the pulp delivered by the outlet to the wire-cloth.

The chamber may be provided with a packing member forming a portion of its wall and located in close proximity to or in contact with the wire-cloth on the breast-roller, and said packing member may be provided with a series of grooves extending in the axial direction of the breast-roller and which act as an interleaving seal against the wire-cloth.

Such packing member may also consist of a roller which rolls against the wire-cloth on the breast-roller, and against the side of which remote from the wire-cloth a member bears to provide the necessary tightness on this side.

The invention is illustrated in the accompanying drawing, in which Figs. 1 and 2 illustrate diagrammatically two different constructional forms of the invention embodied in a machine of the Fourdrinier type.

In the constructional form illustrated in Fig. 1, there is provided a packing member 1 of rubber or other material, the surface of which adjacent the wire-cloth on the breast-roller 2 is provided with a series of grooves extending in a direction parallel to the axis of the roller, and thus forms an interleaving seal, so that water carried along by the wire-cloth is wiped off in front of the said member 1 and forms a water seal at the entrance edge thereof. The said packing member 1 is adjustable by means of screws 3, so that it may be adjusted in different positions relatively to the breast-roller. Attached to the opposite sides of the brackets 10 are end members or closures which form a chamber or box, such end pieces being held in an airtight manner against the rigid portions of the box, while the packings against the breast-roller 2 are made of an elastic material, preferably rubber, which extends close to the roller without necessarily being quite in contact with the same. If desired, these rubber packings are made of a large width, so that interleaving seals may be formed by providing them with suitable grooves.

The chamber 5 thus formed on the upward moving portion of the breast-roller, and which extends to the angle or space formed between the lower wall 4 of the pulp outlet and the wire-cloth running over the breast-roller, will be evacuated to some extent due to the air-pumping action of the wire-cloth passing at a high rate of speed through the chamber, and may be further evacuated through a pipe 6 provided with a regulating valve, by means of a suction pump, which is not illustrated in the drawing, and which may be the suction pump that is used for the suction boxes for the wire-cloth. From the bottom of the chamber 5 a drain pipe 7, also provided with a regulating valve, leads to a receptacle positioned at a lower level, and which may be the same receptacle that receives the water from the wire-cloth suction boxes, and down into which the said pipe 7 must always reach so far that a water seal is formed that prevents admission of air.

In the constructional form of the invention illustrated in Fig. 2, which is the preferred form when sufficient space is available, there is provided, instead of the stationary packing member 1, a roller 8 which is suitably covered with rubber, and which rolls against the wire-cloth on the breast-roller and presses out air and water, thus forming a water seal in front of the roller. In this case tightness is obtained on the other side of the roller 8 by means of a stationary plate 9,

which presses against the roller 8, and which forms an air-tight seal between said roller and the stationary wall 10 of the box.

Also in this constructional form of the invention evacuation of the box is unnecessary under certain conditions, since, owing to the high speed of the wire-cloth, a vacuum is formed to the rear of the roller 8. It is suitable, however, to provide a controlled drain pipe 7, as in the constructional form illustrated in Fig. 1, and if desired, removal of air from the chamber 5 may be effected, for instance, by conducting waste water through an injector.

Fig. 2 also shows a third constructional form which is simpler but less efficient, and according to which, a packing member 11, preferably formed as an interleaving seal of suitable extension in the peripheral direction, is provided directly below the lower side of the pulp outlet 4. In such case the roller 8 and plate 9 are omitted, and the suction box is formed only of the said interleaving seal. A water seal is formed in front of the same by the water carried along by the wire-cloth.

I claim:

1. In a paper-machine of the Fourdrinier type, the combination of a breast-roll, a wire-cloth running over said breast-roll, a pulp outlet for supplying pulp to said wire-cloth above said breast-roll, and a vacuum box located below said pulp outlet in front of the upward moving portion of said breast-roll, a portion of the surface of said breast-roll forming a wall of said vacuum box.

2. In a paper-machine of the Fourdrinier type, the combination of a breast-roll, a wire-cloth running over said breast-roll, a pulp outlet for supplying pulp to said wire-cloth above said breast-roll, a vacuum box located below said pulp outlet in front of the upward moving portion of said breast-roll, a portion of the surface of said breast-roll forming a wall of said vacuum box, and means, other than the moving wire-cloth, for evacuating said vacuum box.

3. In a paper-machine of the Fourdrinier type, the combination of a breast-roll, a wire-cloth running over said breast-roll, a pulp outlet for supplying pulp to said wire-cloth, a vacuum box located below said pulp outlet in front of the upward moving portion of said breast-roll, a portion of the surface of said breast-roll forming a wall of said vacuum box, and a packing member in said vacuum box adjacent the wire-cloth on said breast-roll.

4. In a paper-machine of the Fourdrinier type, the combination of a breast-roll, a wire-cloth running over said breast-roll, a pulp outlet for supplying pulp to said wire-cloth, a vacuum box located below said pulp outlet in front of the upward moving portion of said breast-roll, a portion of the surface of said breast-roll forming a

wall of said vacuum box, and a packing member in said vacuum box adjacent the wire-cloth on said breast-roll, said packing member being provided on its surface directed towards said wire-cloth with a series of substantially parallel grooves forming an interleaving seal against said wire-cloth.

5. In a paper-machine of the Fourdrinier type, the combination of a breast-roll, a wire-cloth running over said breast-roll, a pulp outlet for supplying pulp to said wire-cloth, a vacuum box located below said pulp outlet in front of the upward moving portion of said breast-roll, a portion of the surface of said breast-roll forming a wall of said vacuum box, a packing member in said vacuum box adjacent the wire-cloth on said breast-roll, and means for adjusting said packing member relatively to said breast-roll.

6. In a paper-machine of the Fourdrinier type, the combination of a breast-roll, a wire-cloth running over said breast-roll, a pulp outlet for supplying pulp to said wire-cloth, a vacuum box located below said pulp outlet in front of the upward moving portion of said breast-roll, a portion of the surface of said breast-roll forming a wall of said vacuum box, and a packing member in said vacuum box adjacent the wire-cloth on said breast-roll, said packing member relatively to said breast-roll.

7. In a paper-machine of the Fourdrinier type, the combination of a breast-roll, a wire-cloth running over said breast-roll, a pulp outlet for supplying pulp to said wire-cloth, a vacuum box located below said pulp outlet in front of the upward moving portion of said breast-roll, a portion of the surface of said breast-roll forming a wall of said vacuum box, a packing member in said vacuum box adjacent the wire-cloth on said breast-roll, said packing member consisting of a rotatably journaled roller adapted to roll against said wire-cloth on said breast-roll.

8. In a paper-machine of the Fourdrinier type, the combination of a breast-roll, a wire-cloth running over said breast-roll, a pulp outlet for supplying pulp to said wire-cloth, a vacuum box located below said pulp outlet in front of the upward moving portion of said breast-roll, a portion of the surface of said breast-roll forming a

50 wall of said vacuum box, a packing member in said vacuum box adjacent the wire-cloth on said breast-roll, said packing member consisting of a rotatably journaled roller adapted to roll against said wire-cloth on said breast-roll, and additional means for evacuating said vacuum box.

OSCAR ROLLS.
